CONTINUOUS STRIP DISPENSER FOR TABLETS, PILLS, AND THE LIKE

Egmont Arens, New York, N. Y.

Application April 2, 1953, Serial No. 24,328

Term of patent 3½ years

(Cl. D52—2)

To all whom it may concern:

Be it known that I, Egmont Arens, a citizen of the United States and a resident of the city of New York, county of New York, and State of New York, have invented a new, original, and ornamental Design for Continuous Strip Dispenser For Tablets, Pills, and the like, of which the following is a specification, reference being had to the accompanying drawing, forming a part hereof.

Fig. 1 is a perspective view of the continuous strip dispenser for tablets, pills and the like, this view showing the supporting base member, which is a part of the complete dispenser showing my new design;

Fig. 2 is a perspective view of the supporting base member, the container for holding the individually packaged elements which are to be dispensed not being shown in this view; and

Fig. 3 is a side elevational view of the complete dispenser.

I claim:

The ornamental design for a continuous strip dispenser for tablets, pills, and the like, as shown.
